STROLLER

James Alan Boulbee, 39 Dickson Ave., Artarmon,
New South Wales, Australia

Filed Aug. 3, 1970, Ser. No. 24,272

Claims priority, application Australia Feb. 5, 1970

Term of patent 14 years

Int. Cl. D6—99

U.S. Cl. D14—14

FIG. 1

FIG. 2

FIG. 1 is a front perspective view of a stroller embodying my new design; and

FIG. 2 is a rear elevation view of the stroller shown in FIG. 1.

The left side of the stroller, not shown in the drawings, is identical to the right side.

I claim:

The ornamental design for a stroller, substantially as shown and described.
